UNITED STATES PATENT OFFICE.

LEON CAMMEN, OF NEW YORK, N. Y.

MOLD STEPPING DEVICE FOR CENTRIFUGAL CASTING MACHINES.

Application filed April 5, 1926. Serial No. 99,865.

The present invention refers to unloading gear devices for centrifugal casting machines making individual bars, and deals particularly with that part of the gear which controls the motion of the mold. It is called here mold stepping device, as, because of the novelty of the art, there is no accepted technical name for this kind of apparatus, none having ever been devised or built for the specific purposes here described (previous to this invention). In the illustrations,

Fig. 1 is a general view of the mold stepping device;

Fig. 2 is a similar view of the bar pulling device cooperating with the mold stepping device of Fig. 1;

Fig. 3 a similar view of the valve gear interconnecting the devices shown in Figs.

1 and 2.

When dealing with centrifugal pipe casting machines, the removal of the casting is a simple matter, as there is obviously only one casting in the machine, and one movement or cycle of movements completes the operation. In a bar casting machine, however, there may be from four to as many as thirty-six or more individual bars to remove, which it is obviously impossible to do in one operation. Moreover, in removing the bars it is not desirable to drag them over the surface of the barrel of the mold, as this would wear out the surface and make it rough which in its turn would impart a rough surface to the cast bars. Because of this, the dividing bars 6 were equipped with shoulders 7, as set forth more fully in U. S. Patent to Leon Cammen, No. 1,553,136, September 8, 1925. On account of the presence of these shoulders, the cast bar 5 (corresponding to 1 and 4 in the drawing accompanying the patent above referred to) at the top of the mold, or two or three bars at the top of the mold, lie against the shoulders and not against the surface of the barrel of the mold, and can be withdrawn without hurting the surface of the barrel of the mold. This means, however, that the operation of withdrawing the cast bars from the mold has to be performed in several stages.

The following consideration has also to be taken into account in order to understand fully the purpose of the present invention. Bar casting has to be used with the existing melting equipment, which means open

hearth furnaces, 50 to 120 tons capacity. A bar casting machine will take anywhere from 6 to 20 tons of steel, so that, unless an impractically large number of machines is installed, each machine may have to take more than one batch of metal from each heat, and this means that the machines must be handled with great rapidity, and the bars withdrawn quickly.

Furthermore, with four to five machines operating as a unit, and handling large masses of steel, it is desirable to reduce the amount of labor handling the machines, and yet in nowise impair the reliability of the operation. If four to five machines are deemed in rapid sequence one after another, they will be all operating at the same time, but going through different stages of operation, so that, e. g. one machine will be spinning, a third have the bars pulled, while a fourth will be made ready to receive metal. This means that either a man will have to be assigned to each machine, which will greatly increase the cost of labor, or some of the operations will have to be made automatic. The present invention shows a way to do this latter.

The bars 5 are cast in a mold consisting of barrel 1 and dividing bars 6 equipped, as stated above, with shoulders 7 or equivalent devices in such a manner that in the upper part of the mold the bars 5 lie against these shoulders and leave a space between them and the barrel 1 (2 in Fig. 2). The mold may rotate on rollers (not shown) carried by frame 3. Fig. 2 shows a bar pulling device having, among other things, a pair of jaws 8 and 9 so arranged that they are enabled to grab the bar 5, and pull it out of the casting machine through force applied to rod 10. No novelty is claimed for the use of such a device generally and apart from the other elements of the apparatus herein set forth and described.

Fig. 3 shows the bar withdrawn from the machine (for the sake of simplicity the rollers supporting the bar when in the position shown in this illustration are omitted, and the bar pulling device with its jaws 8 and 9 is shown in a conventionalized form). In order to withdraw the next bar it is now necessary to shift the mold, so as to bring the new bar opposite the jaws of the bar pulling device. This can be done by turning the mold by hand, or by some mecha-

nism like a flywheel jack, but this would be a slow process, and would require for each machine a man on the floor devoting his entire time to this operation. The present invention permits the same thing to be done by a man in a pulpit, by merely pulling a lever, the operation requiring so little time that a single man is enabled to operate several machines. This is accomplished by 10 the mold stepping device here described.

The mold 1 is equipped with gear wheel 15 (or equivalent device, such as a series of holes) having teeth spaces 16. In engagement therewith is a device consisting of tooth shaped bar 14 operated through a linkage by rod 12, which may be connected e. g. with the piston of a hydraulic press. This linkage is so arranged that when the bar 12 is pulled all the way to the right, the tooth 20 14 comes out of engagement with the gear 15. If now the rod 12 is pushed to the left, the tooth 14 engages with the nearest space at the bottom of the gear wheel 15, which in the position shown in Fig. 1 is space 16, and as the rod 12 continues to move to the left, pushes 16 into the position occupied in Fig. 1 by 17. In doing so, it turns the mold 1 a step, and brings a new bar 5 to the top of the mold, in a position to be pulled. As 25 shown in the drawing, Fig. 1, there is one space 16 or 17 to correspond to each dividing bar 6, which means that for each cycle of operations of rod 12 one casting 5 will come to the top of the mold, and one casting will be pulled. If necessary however 30 the gear 15 and the stroke of the rod 12 may be so arranged as to turn the mold through an angle corresponding to two or more castings 5.

40 The operation of the device, as described thus far, consists therefore of the following steps: Jaws 8 and 9 grab casting 5 and through the force exerted on rod 10, as by a hydraulic device not shown, pull it out of mold 1. While this is being done, the bar 12 and block 28 are shifted to their uttermost position on the right. After casting 5 has been completely pulled out, the bar 12 is moved to the left, and in doing 45 so, it causes the engagement of tooth 14 with space 15, and the turning of the mold through one step which brings another casting into a position which makes it suitable for withdrawal. Such operation would however 50 require constant attention on the part of a man to manipulate at proper times the controls setting into motion rods 10 and 12. To avoid this, the device shown in its essential features in Fig. 3 has been devised. In 55 this, rod 10 carries piece 11 which is simply a rod or strip of metal. As the rod 10 comes into the position shown in Fig. 3, which is the position which it occupies when the casting 5 has been completely withdrawn from 60 mold 1, bar 11 hits valve handle 18 and

brings it from a position parallel to 11 into the position shown in the drawing. In changing its position, handle 18 opens a valve which admits fluid under pressure in the direction of the arrow (seen at left of 18) into cylinder 21 and thus operate rod 12. In this way, rod 10 by its motion controls the motion of rod 12. An exactly similar device can be used to control the motion of rod 10 by that of rod 12. When 70 rod 10 moves into its forward position (to the right in Fig. 3), bar 11 moves also forward releasing the pressure on 18. The powerful spring 19 then pulls the handle 18 into such a position that the liquid pressure acts on rod 12 in the opposite direction, and causes it to move to the right, returning it to the original starting position. The details of the valve arrangement are not shown, as with the above description any 80 engineers skilled in the art would know how to make such a device operate with oil or air under pressure, or by electrical means.

Further, a device may be provided to stop the operation of the entire system when all 90 the bars have been withdrawn. Thus, a disc 30 may be provided with feather springs 31, 32, etc., so arranged that the disc 30 will turn through one step every time pressure is brought on one of these springs in the 95 direction from right to left, but pressure on the springs in the opposite direction will not affect the disc. There are as many of these springs as there are strokes by rod 10 to be made, the disc being so arranged that 100 every time the rod 10 goes into the position shown in Fig. 3, bar 11 hits one of the springs 31, 32, etc. causing the disc to turn through one step. As the last cast bar comes out, the spring 37, which is longer than the 105 rest, trips the switch 38, and discontinues the operation of the system. If desired, the same tripping of the switch may cause a light to flash out, or a bell to ring, or the like, signalling that all bars are withdrawn. The details of construction of this tripping 110 device need not be described here, as with the above description to guide him, any electrical or mechanical engineer can make such a device to suit his particular conditions.

As the need for a device like the one set forth and described above is not apparent where only very few castings are made in a machine, the claims have been limited to a 115 machine producing not less than four separate castings at a time.

There have never been built any machines for extracting castings from a centrifugal machine where more than four separate castings were cast at a time and the art has been practically non-existent prior to this invention. There are therefore no established names for the various devices described here, and these devices had to be described in the 120 125 130

roundabout way employed in this specification and claims.

I claim:

1. In a machine for centrifugal casting means disposed with relation to the mold of said machine to withdraw a part of the castings therefrom, and coacting means for moving said mold through a predetermined angle after such withdrawal.
- 10 2. In a machine for centrifugal casting, means disposed with relation to the mold of said machine to withdraw a part of the castings therefrom, and means controlled by the withdrawal means for moving said mold through a predetermined angle after such withdrawal.
- 20 3. In a machine for centrifugal casting, means disposed with relation to the mold of said machine to withdraw a part of the castings therefrom, mechanism controlled by the withdrawal means for moving the mold of said machine through a predetermined angle after such withdrawal, and adjusting means to regulate the operation of said withdrawal means by the extent of the mold movement.
- 25 4. In a machine for centrifugal casting, means for successively withdrawing said

castings whereby only a part of the castings is withdrawn at a time, and mechanism controlled by said withdrawal means for re-setting the mold in readiness for another withdrawal operation.

5. In a machine for centrifugal casting, means for successively withdrawing said castings whereby only a part of the castings is withdrawn at a time, mechanism controlled by said withdrawal means for moving said machine after a withdrawal to present a succeeding part of castings to the withdrawal means, and other mechanism to prevent the communication of further movement to the machine after the withdrawal of the last of castings therefrom.

6. In a machine for centrifugal casting, a mold, means disposed with relation to said mold to withdraw a part of the castings therefrom, engaging means upon said mold, and means to move said mold through a predetermined angle, said last means co-acting with the engaging means on the mold and controlled by the withdrawal means previously referred to.

Signed in New York, in the county and State of New York, March 31, 1926.

LEON CAMMEN.
